VOLUME CONTROL

Winfield R. Koch, Haddonfield, N. J., assignor to
 Radio Corporation of America, a corporation
 of Delaware

Application June 15, 1942, Serial No. 447,009

9 Claims. (Cl. 179—171)

My present invention relates to volume controls for radio receivers, and more particularly to a manually-adjustable volume control device for a portable receiver of the battery type.

Portable receivers of the battery type are common at the present time. As the size of the receiver is reduced, say to vest pocket dimensions, the factor of minimized battery drain becomes extremely important. Control over the receiver output volume, in such diminutive receivers, must be effected with minimum distortion and minimum battery drain. The usual methods of gain control, applied to an audio amplifier stage for example, are undesirable. Grid bias control produces distortion; audio input level control engenders maximum battery drain.

Accordingly, it may be stated to be one of the main objects of my present invention to provide a method of, and means for, securing volume reduction in a portable receiver of the battery type with minimum battery drain; the method employing concurrent degenerative feedback to improve fidelity.

Another important object of my invention is to provide an audio amplifier whose output energy level is regulated by varying the screen voltage thereof thereby to provide distortionless and efficient volume control.

Another important object of my invention is to provide a volume control for a signal amplifier, which control varies the positive voltage of a positive auxiliary electrode; operation of the control subsequent to minimum volume position resulting in actuation of an "on-off" switch to render the amplifier ineffective.

Yet another object of my invention is to provide in a battery-operated portable receiver a manual volume control which simultaneously varies screen voltage and effects variable degeneration thereby to improve fidelity with minimum battery drain.

Still other objects are to improve generally the efficiency and simplicity of battery-operated portable receivers.

The novel features which I believe to be characteristic of my invention are set forth with particularity in the appended claims; the invention itself, however, as to both its organization and method of operation will best be understood by reference to the following description taken in connection with the drawing in which I have indicated diagrammatically a circuit organization whereby my invention may be carried into effect.

Referring, now, to the drawing, there is shown a rectangle designated "Portable receiver." It

is to be understood that while my invention has application to various types of receivers portable or non-portable, it has especial utility in connection with diminutive portable receivers of the battery-operated type. Such receivers are sufficiently compact to fit into a vest pocket; the batteries are, therefore, small and current drainage is an important factor in design. Such receivers have a self-contained signal pick-up device, as, for example, a loop. The reproducer is usually a crystal ear-phone reproducer of the type used in deaf-aid apparatus.

In the drawing I have only shown the audio amplifier tube 1 and its associated circuits. The tube 1 has a filament 2, a signal input grid 3, a screen grid 4, a suppressor grid 5 and a plate 6. The signal grid 3 may be coupled to the load resistor of a demodulator, or to the plate load of a prior audio amplifier. The coupling condenser 7 acts to couple the grid 3 to the prior stage; grid return resistor 8 connects grid 3 to ground. The battery for energizing the tube is denoted by numeral 9.

The battery is divided into two sections. One 25 of these is the "A" section for heating the filament 2. The other section is the "B" section for supplying the plate and screen voltages for tube 1. The negative terminal of battery 9 is grounded through the spring metal switch arm 10. The fixed contact 11 is directly connected to the minus terminal of battery 9. The fixed end of arm 10 is grounded, while the free end of the arm 10 is provided with an insulation stud 12. The switch 11—10 is the "on-off" switch 30 of amplifier tube 1, and, hence, of the entire receiver. The plate 6 is connected to the positive terminal of battery 9 through a path comprising the choke coil 13 and lead 14. One terminal of the filament 2 is grounded, while the other terminal is connected to the positive terminal of the "A" section of battery 9. Leads 15 35 may be connected to filaments of prior tubes so that the "A" section of battery 9 heats the filaments of all the receiver tubes.

The screen grid 4 is connected to the lower end 45 of choke coil 13 by means of an adjustable rheostat arm 16. The rheostat comprises a plurality of resistors 17, 18 and 19. These resistors are arranged in the order of increasing magnitudes. They have common terminals connected 50 to the screen grid 4, while the opposite terminals are adapted to be successively contacted by arm 16 for the volume control adjustment function. An additional contact point 20 is connected directly with the screen grid so that when the

volume control is at position 20—16 the volume level of the receiver is maximum. When the arm 16 is adjusted to connect resistor 17 in the screen circuit the volume is reduced. As the arm 20 is further adjusted successively to connect the respective resistors 18 and 19 into circuit with the screen grid, the volume level is still further reduced. When resistor 19 is in circuit with the screen grid, then the volume level is a minimum. Merely by way of illustration, it is pointed out that resistor 17 may have a magnitude of 0.2 megohm; resistor 18 may have a value of 1 megohm; while resistor 19 may have a value of 10 megohms.

Upon adjusting arm 16 in a counter-clockwise sense from the minimum volume position, the free end of arm 16 will open switch 11—10 due to pressure against insulation stud 12. Hence, when the contact arm 16 is in position such as to contact stud 12, the receiver will be in "off" condition. Those skilled in the art are fully acquainted with the manner of constructing an "on-off" switch so that when arm 16 is adjusted to open switch 11—10, the latter will remain fixed in that position until it is actuated to increase the volume.

A condenser 30 connects the screen grid 4 to ground, and acts to bypass currents of high audio frequencies from the degenerative path; the latter path is provided by the successive resistors inserted in the screen grid circuit. The anode choke coil 13 will prevent rapid decrease of gain at low audio frequencies when the volume control arm 16 is adjusted to decrease the volume level. Audio voltage developed across the plate load is transmitted through the coupling condenser 40 to the crystal reproducer. It will be noted that one terminal of the crystal reproducer is connected to the ungrounded end of resistor 41, while the other terminal is connected to the grounded end of the resistor.

Capacitor 40 serves to block direct current from the crystal reproducer. However, any leakage through this capacitor might charge up the capacitor formed by the crystal reproducer. Resistor 41 bypasses any such leakage current. By grounding the lower end of the crystal reproducer, the shock hazard to the listener is reduced. Furthermore, audio currents flowing through the cathode-anode path in the tube 1 complete their circuit through the crystal reproducer, thus keeping them out of the "B" battery and avoiding the necessity of bypassing the battery as would otherwise be required to keep down unwanted feedback.

In explaining the operation of the present invention, it is pointed out again that in battery-operated receivers of this type the battery drain should be as small as possible. The usual volume control means do not act to reduce the battery drain when only a limited output level is desired, or when a strong signal tends to overload the output tube. By inserting a variable resistor in the screen circuit of the final audio amplifier tube, reduced volume can be secured by reducing the screen voltage. At the same time the screen resistor introduces a negative feedback for audio frequencies thereby to reduce any distortion caused by the amplifier tube. By combining the "on-off" switch with the minimum volume control position zero volume is readily secured. Because the filaments heat very rapidly, this system for obtaining zero output level is satisfactory.

Some acoustic tone compensation is also secured by virtue of the following action. The reduced plate current of the tube through the inductance of coil 13 will cause the inductance to increase. 5 This tends to improve the low frequency response relative to the middle registers. The capacitor 30 prevents the negative feedback from being as effective for high audio frequencies as for the middle register. Therefore, as the volume control is adjusted toward the minimum volume position, the amplification of the median audio frequencies is reduced faster than that of the higher and lower audio frequencies. In actual tests made 10 on this circuit, it was found that on a strong local station, with reduced volume control setting, the screen voltage on the tube was only 10 volts instead of the applied plus 45 volts.

The negative feedback action occurs in the following manner. By inserting a resistor in the 20 screen circuit audio frequency voltages appear across the inserted resistor. The electrons reaching the plate 6 are, therefore, affected by two grids. These grids are the control grid 3 and the screen grid 4. The voltages of these two grids 25 are in opposition. That is, when grid 3 is at the positive peak of the audio cycle, the screen grid 4 will be most negative. If a sine wave is applied to grid 3, and the tube is not linear, the voltage appearing on grid 4 will be non-sinusoidal, and 30 of such shape as to correct for the non-linearity of the portion getting through to the plate. Thus, the larger the magnitude of the resistor inserted in circuit with grid 4, the larger is the negative feedback effect and the less will be the audio gain 35 through the tube. Of course, instead of the tapped type of switch shown in the screen grid circuit, a continuously variable resistor may be employed for finer control.

40 While I have indicated and described a system for carrying my invention into effect, it will be apparent to one skilled in the art that my invention is by no means limited to the particular organization shown and described, but that many modifications may be made without departing 45 from the scope of my invention, as set forth in the appended claims.

What I claim is:

1. A method of operating a signal amplifier of the type including a screen grid tube which includes applying signals to said tube, deriving amplified signal energy from the tube, varying the direct current voltage of solely the screen grid of the tube to control the signal output level thereof, and concurrently developing signal voltage in the screen circuit of the tube which is in degenerative phase with the signals applied to the tube thereby to reduce distortion caused by the amplifier.

60 2. A method of operating a signal amplifier of the type including a screen grid tube which includes applying signals to said tube, deriving amplified signal energy from the tube, varying the direct current voltage of solely the screen grid of the tube, concurrently developing signal voltage in the screen circuit of the tube which is in degenerative phase with the signals applied to the tube, and concurrently varying the screen grid voltage and said degenerative voltage magnitude in opposing senses to control the level of 65 said amplified signals with simultaneous reduction of distortion caused by the amplifier.

70 3. In a portable receiver of the battery-operated type, an amplifier provided with at least a cathode, signal grid, screen grid and plate, means for applying audio signals to the signal grid, a battery for providing positive potentials

for said screen grid and plate, a battery for energizing the cathode to emit electrons, variable resistor means connected in circuit with said first battery and solely said screen grid for varying the effective positive voltage of solely the screen grid, and means for bypassing solely the higher audio frequencies from said resistor whereby said variable resistor is capable of providing a variable degree of degeneration of audio signal voltage throughout the range of its adjustment.

4. In a portable receiver of the battery-operated type, an amplifier provided with at least a cathode, signal grid, screen grid and plate, means for applying audio signals to the signal grid, a battery for providing positive potentials for said screen grid and plate, a battery for energizing the cathode to emit electrons, variable resistor means connected in circuit with said first battery and screen grid for varying the effective positive voltage of the screen grid, said variable resistor providing a variable degree of degeneration of audio signal voltage throughout the range of its adjustment, and means, responsive to adjustment of said screen grid voltage variation means, for rendering the second battery ineffective to energize said cathode at the minimum positive voltage setting of said voltage varying means.

5. The method of reducing the gain of an electronic amplifier having a filament, at least two grids, and an anode, and in which the electron stream is modulated by a signal impressed on one grid; which includes reduction of amplitude of the modulated electron stream by opposing signal voltages on the second grid obtained by consecutively connecting resistances of increasing values between solely the second grid and a point on the voltage supply positive with respect to said filament, and thereafter interrupting current to said filament.

6. A method of operating a signal amplifier of the type including a screen grid tube which includes applying signals to said tube, deriving amplified signal energy from the tube, developing signal voltage in the screen circuit of the tube, varying the direct current voltage of solely the screen grid of the tube, and concurrently varying the signal voltage in the screen circuit of the tube which is in degenerative phase with the signals applied to the tube.

7. A method of operating an audio signal amplifier of the type including a screen grid tube which includes applying audio signals to said tube, deriving amplified audio signal energy from the tube, varying the direct current voltage of

solely the screen grid of the tube, developing audio voltage in the screen circuit of the tube which is in degenerative phase with the audio signals applied to the tube, and concurrently varying the screen grid voltage and said degenerative voltage magnitude in opposing senses to control the level of said amplified audio signals.

8. In a portable receiver of the battery-operated type, an amplifier provided with at least a filament, signal grid, screen grid and plate, means for applying audio signals to the signal grid, a battery for providing positive potentials for said screen grid and plate, a battery for energizing the filament to emit electrons, variable resistor means connected in circuit with said first battery and screen grid for varying the effective positive voltage of the screen grid, said variable resistor providing a variable degree of degeneration of audio signal voltage throughout the range of its adjustment, and means responsive to adjustment of said variable resistor to minimum volume setting for interrupting current to said filament.

9. In a portable receiver of the battery-operated type, an audio amplifier tube provided with at least a cathode, signal grid, screen grid and plate, means for applying audio signals to the signal grid, a battery for providing positive potentials for said screen grid and plate, means for energizing the cathode to emit electrons, variable resistor means connected in circuit with said first battery and screen grid for decreasing the effective positive voltage of the screen grid thereby to reduce the tube gain with small battery drain, said variable resistor providing a variable degree of degeneration of audio signal voltage throughout the range of its adjustment, a capacitor operatively associated with said variable resistor for preventing degeneration from being as effective for high audio frequencies as for median audio frequencies, a coil in circuit between the plate and a desired point of the battery, said coil having developed thereacross amplified audio signal voltage, said coil having an increase in inductance in response to reduction of plate current thereby to improve the low audio frequency response relative to median audio frequencies, and means, responsive to adjustment of said screen grid voltage variation means, for rendering the cathode energizing means ineffective to energize said cathode at the minimum positive voltage setting of said voltage varying means.

WINFIELD R. KOCH.
